METHOD AND APPARATUS FOR SMOKING

Joseph Z. Delinda, New York, N. Y.

Application February 27, 1932, Serial No. 595,476
In Germany March 20, 1931

2 Claims. (Cl. 131—22)

My invention relates generally to a new method and apparatus for smoking and to a process for preparing the necessary product in a natural or synthetic way and apparatus for using the same.

It is well known that in the burning of tobacco in smoking, such as in a cigar, cigarette or pipe, many products or compounds are formed which have a harmful or irritating effect upon the human organs generally, and particularly upon the mucous membrane in the nasal passages and respiratory organs. Some of these substances are, for example, nicotine, pyridine, ammonia, nitric acid, hydrogen sulphide, prussic acid, collidine which alkaloid is more poisonous than nicotine, and many others such as carbon monoxide which from a practical point of view is one of the most harmful elements of tobacco smoke. These compounds may either be formed upon the burning of the tobacco and other plants used in this industry or from the burning of the paper and glue in the case of cigarettes. Various means have been suggested for avoiding the disadvantageous effects of these compounds but none has met with any full success.

There are, of course, other disadvantages in the present methods of smoking, such as the danger of fire in lighting the tobacco or in the combustion of the tobacco which is a necessary element. There is also the disadvantage of inhaling fumes of a relatively high temperature which in itself effects the nasal and breathing passages and is responsible for the many colds contracted by smokers. In this same connection the hot ends of cigarettes, cigars or pipes tend to increase the flow of saliva and other digestive juice and to be absorbed therein and may be indirectly responsible for certain mouth and stomach diseases. Also, of course, there is the problem of disposal of the waste products, such as stubs and ashes.

Another feature which is not usually considered is that of the relatively inefficient use of the full amount of tobacco in a cigar or cigarette, or even in a pipe, for in any case a considerable portion is wasted.

One of the primary objects of my invention is to eliminate the disadvantages stated above.

Other objects and advantages of my invention will appear from the following description and as illustrated in the drawings.

My invention consists essentially in burning or otherwise distilling off or converting to vapors a material which forms a desirable vaporous material, such as tobacco, or other plants, such as

licorice or eucalyptus or others, either alone or in combination. The smoke or distilled matter from this burning operation is then purified by condensing, filtering, scrubbing, washing, blending or otherwise removing or diminishing undesirable portions after which it is compressed and puts into containers. My product may, of course, be obtained synthetically by combining the essential elements of a natural smoke or by adding certain substances to a natural smoke product. Such added material may either be similar to and thus increase the percentage of components already present or may be different constituents from those present. This compressed material is then utilized for the pleasure of the user by means of releasing it in suitable amounts into the mouth of the user. Such a means may approximate the size and shape of a cigar or cigarette, if desired, or other forms may be used such as a pipe or a central vessel which has flexible tubular conductors similar to the narghile. I, of course, do not wish to be limited to any specific method for preparing or using my product. Further, I do not wish to be limited to a specific means for preparing or using my product although I have disclosed several specific forms for such a use in my drawings, in which:

Figure 1 represents a schematic view of an apparatus suitable for producing my compressed product;

Figure 2 represents a cross sectional view of an apparatus for using my compressed material;

Figure 3 discloses a modification of Figure 2;

Figure 4 is another modification of my smoking means;

Figure 5 is a detail view of Figure 4;

Figure 6 is a cross sectional view of another modification of my smoking means;

Figure 7 is an enlarged cross section taken at 1—7 of Figure 6;

Figure 8 is an enlarged cross section taken at 8—8 of Figure 6;

Figure 9 is a perspective detail of a portion of the apparatus of Figure 6;

Figure 10 is a broken sectional detail of the apparatus of Figure 6 taken along the line 10—10 of Figure 7;

Figure 11 is a broken cross sectional detail of one position of the apparatus of Figure 6;

Figure 12 is another broken cross section of a position of the apparatus of Figure 6; and

Figure 13 is also a broken cross sectional detail of a third position of the apparatus of Figure 6.

Referring more particularly to the drawings in

which like reference characters denote like parts, reference character 1 of Figure 1 denotes a retort for carrying on the combustion and formation of my material which is later to be compressed. This combustion chamber may have at its lower portion 2 a burner or heating means which may be used to start or facilitate the combustion of the raw material 3 which is shown resting on the trays 4 one above the other. Air 10 may be admitted at 2 if desired and ashes or refuse removed therefrom. These trays may be inserted and removed through the doors 5. The distilled products from the tobacco or other material passes upwardly into the retort head 6 and 15 may be forced by the fan 7 or other means and its operating motor 8 into the combustion or distillate 9 which is controlled by the valve 10. This vapor line discharges into a vessel 11 in which certain of the more easily condensable materials 20 are knocked out or removed from the distillate. In this vessel 11 and those described later the condensed or segregated material may be collected and removed and used as desirable by-products. The remaining gaseous material then 25 passes through the conduit 12 which is controlled by the valve 13. This conduit has in it filters, scrubbers or washers 14 for removing certain other of the undesirable constituents. These filters may have on them or consist of certain catalytic or treating materials, if desired, for removing or converting undesired constituents or for giving to the gaseous material certain desirable added properties, such as color, aroma or vitalized characteristics. This catalytic or other 30 treatment may also consist in so modifying the distillate that it tends to equalize the vaporization points of the several constituents and thus permits upon revaporization of the compressed product a gaseous material having substantially all 35 the characteristics of the distillate prior to compression. For example, carbon-monoxide may either be removed or converted to carbon-dioxide. In certain cases it has been found desirable to treat the gaseous material with 40 ultraviolet, infra-red rays or other radiations and emanations to vitalize them to a desired degree, and such treatments may take place, if desired, at this point prior to compression or may be given to the material 45 after compression. In certain cases it has been found desirable to add to the product either before or after compression certain desirable microscopic health promoting organisms, or such certain bacteria not alone to help the peculiarity 50 of the flavor of the gas because tobacco flavor can be substantially regulated by bacteriological method, but also to serve as a desirable safeguard against the development of other bacteria, which may develop and produce undesirable effects, or even help against chemical changes. The material from the condenser 15 may again be passed 55 through an apparatus 16 controlled by valve 17 and again treated or filtered before passage to the condenser 19. This step or sequence of steps can be employed as many times as necessary. From this last vessel the material is drawn off 60 through the line 20 into a compressing means 21 which I have illustrated in a conventional fashion. This compressing means may be fitted if desired with ball valves 22 and the compressed 65 material passed through the line 23 into a receiver 24. The compressed material may then be withdrawn through the line 25 controlled by the valve 26 and put into dispensing containers 70 75

27, as shown in Figures 2, 4 and 6. Such an industrial oxidation, in particular burning, of the raw material permits the accurate zoning of the heat in separate furnace compartments along the retorts which may be tubular or trays 5 as shown, together with varied methods of withdrawing vapors and gases. This operation may be carried on under pressure or under vacuum if desired, and in the presence of reducing gases. Such oxidation allows full control and regulation 10 of the heat applied. Other methods of extracting the desired compound may be used.

The apparatus shown in Figure 2, and the remaining figures of the drawings relate to certain specific means for utilizing the compressed material. The apparatus of Figure 2 consists essentially of a tubular portion 28 threaded to another tubular portion 29. The container 27, it is seen, fits into the outer part 28. The curved end of the part 28 is adapted to be inserted into the 20 mouth. A cap 30 screws on to the container 27 and may be used to turn the container within the part 28 and turn on or shut off the flow of the material from within the container. The neck of the container 27 is shown threaded into 25 a cap 31 which is fixed in the portion 29. This cap has in it a small hole 32 which is adapted to rest in line with a hole 33' in the neck of the container 27 upon proper turning of the container. The expanded combustion material passes from 30 the chamber 28' in the portion 28 through the ducts 33 into the expansion chamber 34 in the portion 29 and thence through the duct 35 into the chamber 36 from which it may be withdrawn through the orifice 37 into the mouth. I have shown ducts 38 which connect the duct 35 with the air so that upon drawing out of the duct 37, a regulated amount of air will be mixed with the expanded combustion material. In order to prevent a backward flow into the expanding chamber 40, I have equipped the container with a check valve 39. This valve 39 opens upon sucking out the gases while preventing the outward flow of such gases from the chamber 34 without such sucking by the user. The valve normally remains 45 in closed position.

In Figure 3 I have disclosed a modification of the expansion chamber 36. In this form I utilize a coil 40. I have also shown in Figure 3 a modification 41 which simulates a cigarette or cigar 50 end and may even be arranged to permit the out flow of smoke. This portion may be used in a similar fashion to the cap 30 for turning on or shutting off or otherwise regulating the flow of combustion material. 55

In Figure 4 I have disclosed another modification of my means for using the compressed material. This consists in an outer shell 42 which may be formed similarly to a cigarette or cigar holder. The container 27 is shown inserted in 60 this shell. The cap 43 is threaded into the container and may be used to close the same or to simulate a lighted end of a cigarette. The container may be threaded into the outer shell, as shown at 44. Ducts 45 permit the inward passage 65 of air into the expansion chamber 45' which may also be fitted with a check valve as shown at 39 of Figure 2. 46 designates a valve which is shown in detail in Figure 5. This valve may be opened 70 and closed by means of the connection with the forked arm 47 which is moved by the lips pressing on the lever at 48. This lever is pivoted as shown at 49. The compressed material passes out through the opening 50 into the expansion 75

chamber 45 where it mixes with air passing into the ducts 45. The compressed smoke may then be drawn out through the orifice 50' into the mouth. By releasing the pressure of the lips against the lever 48, the valve 46 will be closed and the supply of smoke cut off.

I have shown a device in Figures 6 to 13, inclusive, which is a preferred form of my smoking apparatus. This device consists primarily of a part, or central section 51, a mouthpiece 52 and the container on unit 53, containing the compressed material 53' which is set into the central section 51. The unit containing the compressed material 53' is fitted with a neck portion 54 and mother sleeve 59 which have small openings or orifices 55 and 59'. The mouthpiece is fitted to the central part 51 in such a manner that it has a longitudinal movement and is adapted to be relatively easily moved in and out along the portion 51 into three positions, and it is by means of this positioning of the mouthpiece that permits a certain quantity of smoke to be released from the container 53 expanded and mixed with air, if desired, and drawn into the mouth of the user.

I have shown for this purpose indentations on the central portion 51 and embossments on the mouth piece 56 which fit into the indentations and by a slight pull or push may be changed from one position to another. Other means, as for instance by rotation or by pressure of the lips, of course may be used for permitting this movement.

The central portion 51 has in its upper inner part an inner cylindrical well as shown in the drawings by the reference character 58. This inner well 58 has at its lower edge a projecting ring 58' which will be later described in connection with limiting the movement of the mouthpiece 52. Inserted in this inner cylindrical portion 58 there is the part 59 which can be seen particularly in the cross sections of Figures 7 and 8. This part is preferably made square or flat sided to prevent turning and is inserted into 58 so that the threaded neck portion 54 may be screwed into it to such a point that the orifice 55 of the neck is in line with a small orifice 59' in the part 59 which is further in line with the orifice 58'' in the cylindrical inner section 58.

The container 53 is adapted to be sold together with the mother sleeve 59 which is screwed on the neck portion. In this way the mother sleeve 59 covers the orifice 55 of the neck and its own orifice 59' is not in the alignment with the orifice of the neck. When the container 53 is inserted in 58 up to the limit, the container 53 is screwed out from its mother sleeve until both orifices 55 and 59' are in alignment which is ascertained by the embossment and indentation meshing at the point 57. When smoking is interrupted 53 could be screwed back in the mother sleeve and taken out from the holder.

In addition to the upper flange of the inner cylindrical portion 58 which connects it to the outer shell 51, there are vertically extended segments 60 which join the inner cylinder with the outer cylinder and extend from the lower abutting ring 58' upward to somewhat less than the upper ring so that an opening 61 is left between each of the segments 60 and the upper ring, or flange, of 58. These segments and the openings above them will later be described in connection with dispensing a given amount of compressed material into the expanding chamber portions of my device.

Connected to the mouth piece 52 there is an extending tube 62 which expands into a flange 63 acting as a piston within the outer shell 51. Connected to this flange at one portion there is the arm 64 which has at its upper end a downwardly extending portion 65, the purpose of which is to limit the movement of the mouthpiece and tube 62 by bearing against the upper flange 58 on one movement and against the lower extending ring 58' on its outward movement. Also connected to the flange 63 there is an upwardly extending portion 66 which operates within the segment formed by the side walls 60. Connected to this segment 66 there is the downwardly extending portion 67 which also may bear against the extending ring 58', limiting the outward movement of the mouthpiece. The portion 68 is an upwardly extending continuation of 67 and bears against the outer surface of the inner cylinder. The part 69 is connected to 68 and fills transversely the chamber formed by the segments 60 and the cylinder walls 51 and 58. The upper part of 66 and the part 69 are adapted to operate as pistons between the side wall segments 60 and act as the lower and upper limits with these segments to form a small chamber. The vertical portion 68 has in it a small orifice 70 which, when properly positioned, will be in line with the orifice 55. It should be noted that when the mouthpiece and tubular portion 62 are positioned in their furthest upward movement that the side wall segments 60 do not cover the sides of the chamber formed by the parts 66, 68 and 69. The operation of this portion of the apparatus will be described later.

At the lower portion of the tube 62 there are the orifices 71 which connect the inner portion of the tube with the expansion chamber 72. There are also the orifices 73 in the tube which are permanently in alignment with the orifices 74 in the mouthpiece and permit a free opening between the chamber 72 and the ducts 75 when the tube 62 is positioned at an intermediate point in alignment with the orifices 76 in the lower portion of the central cylinder 51. This positioning takes place when the mouthpiece is placed in an intermediate position as shown in Figure 13. It is to be noted that the orifices 76 are in an upwardly extending collar connected with the inner central cylinder 51 which encloses the tube 62. The equalizing piston 77 also encircles the tube 62 and is adapted to freely move along the tube and within the cylinder formed by the central portion 51. Its lower movement may be limited by the abutment 78 on the tube 62 which also acts to limit the outward movement of mouthpiece 52. There are orifices 79 in the central cylinder 51 which connects its inner space with the atmosphere and the flange 77 may pass upwardly beyond these openings and permit air to be drawn into the expansion chamber 72 or if placed near flange 63 no outer air will mix with the smoking product.

The container for the compressed material 53 may be of the type 27 shown in Figure 2 or in Figure 4, or other suitable arrangements. I have, however, shown in my device in Figure 6 a modified form which may have certain advantages. In this arrangement I have a cylinder head 80 which is adapted to move within the container 53 to retain the gases or compressed vapors therein. In order to compensate for the diminution in their volume and to maintain a constant pressure. I have placed the spring 81 in such a position that it will continually force the cylinder head down

through the cylinder and tend to keep an even pressure therein. Other such means may be used. The orifices 82 equalizes the pressure back of the head with the outer air.

5 I have also shown an opening 83 which permits the determination of the position of the cylinder head and thus allows the relative amount of material still in the container to be determined. In order to facilitate this determination, I may 10 use a small roller 84 containing a tape or any material which may indicate, either by color or figures, or other means, the relative amount of material in the container. This is accomplished by passing the tape over a pulley 85 and connecting it to the cylinder head as at 86.

15 The operation of my device is as follows:

Container 53, together with its mother sleeve 59 of the neck portion 54, is inserted in the upper central part 58 of the cylinder 51. An upwardly unscrewing of the container 53 from the mother sleeve 58 until the limits of the embossment 57 will place the orifices 55 and 59' in line. This may be indicated by the alignment of the embossments and recess 57. The mouthpiece 52 is then 20 moved outwardly as far as it will go which movement is limited by the portions 65 and 67 bearing against the extending ring 58' and by the extending collar of the cylinder 51 against the ring 78. This position is shown in detail in Figure 11. It is 25 seen that the orifices 55, 59', 58" and 70 are then in alignment and the compressed material thus permitted to flow into the chamber 70' formed by the side walls 60, 68 and 69, the upper portion of 68 and the cylinder wall 51. When this chamber has been filled, the mouthpiece is moved 30 inwardly as far as it will go. This movement positions the chamber 70' beyond the side walls 60 and permits the compressed material therein to flow into the chamber 63' which opens into the tube 62 and thus flows into its inner portion 62'. 35 Expansion takes place in this chamber and the released distillate flowing out through the orifices 71 into another expansion chamber 72. The expansion may be such that the cylinder head 40 71 is forced along the tube 62 and beyond the openings 78 unless the openings are located near the flange 63. The gases thus become equalized in pressure with the outer air. This positioning is shown in detail in Figure 12. It is to be noted 45 that the expanded material cannot be drawn into the mouth of the user through the duct 75 as the orifices 73, 74 and 76 are not in alignment.

50 The mouthpiece is then moved to an intermediate position as shown in Figure 13 in which the orifices 73, 74 and 76 are in alignment. The user in drawing on the mouthpiece then draws the expanded material out through the duct 75 and also may in certain cases with proper arrangement draw with it a desirable amount of air 55 which is entered through the orifice 79. This, of course, draws back the cylinder head 77. The operation may then be repeated at the will of the user. This operation may be carried on merely by holding the mouth piece in the mouth and by 60 moving the central portion 51 back and forth by the hand or by the lips. The flow of compressed material may be stopped at any time by moving the mouthpiece against the central portion 51 due to the downwardly extending part 67 covering the orifice 55 when in this position or by screwing 65 the mother sleeve 59 on the neck 54 of the unit 53 which enables one to take out the unit 51 from the holder 52 with loss of compressed material. Thus, the device may be laid down and 70 when not in use no loss of compressed material 75

will take place except when in use and at the will of the user.

It is seen, therefore, that it is possible to regulate the pressure under which the smoking products would be sucked in by the user and also that the smoking product or compressed vapors, cannot escape of its own accord but is regulated by the user. The products first pass to a distributing chamber and then into a pressure equalizing chamber where in certain cases they may be 10 mixed with air. Then they pass into the mouth of the user as desired. My device may be modified in these details without departing from the spirit of my invention. If desired, the container may be doubled-walled or otherwise adapted to 15 protect it against changes in temperature. The container and smoking apparatus may be made from any suitable material.

In general, therefore, I have developed a smoking process which makes use of all the constituents of the combustible and distillate material inasmuch as the vaporous or gaseous distillate portions may be compressed in such a manner as to be used in my smoking device. The waste product from the combustion, such as the ash, 20 may be utilized to recover any valuable components such as its mineral salts. The constituents which are removed from my distillate either prior or subsequent to compression may also be utilized. For example, the nicotine separated has valuable 25 uses as an insecticide and may all be recovered and sold if desired. Pyriden recovered may be used as a denaturant. Resins and wax may also be used. In other words, by my process the combustion may be completely regulated and the conditions controlled so that the most advantageous operation will be carried out, whereas in the ordinary methods not only is a considerable portion of the material to be burned, actually wasted, but nearly all of the valuable by-products are lost. 30 Furthermore, the vaporous products may be treated to give them any desirable characteristics. The noxious constituents may be removed or if desired a certain portion of them may be allowed to remain to give their usual palliative 35 effective as present in ordinary smoking. As I have already stated, they may be treated in different ways to give them desirable characteristics. I do not wish to be limited solely to the compression 40 of my combustion gases. It may be found desirable to absorb them in some material which will release them when desired. Such a material might be an absorbent, dry material or gel such as a silica gel, or air absorbent liquid may be used. It may also be compressed to a solid or liquid 45 form under certain conditions.

All of the usual disadvantageous characteristics of smoking have been eliminated by my method of smoking. It is not necessary for the user to carry on any combustion whatsoever. Furthermore, smoking by my method makes it possible to eliminate all of the dangerous characteristics of ordinary cigarette, cigar or pipe smoking in regard to the health of the user. The smoke which is drawn in by the user will be cool and may be non-poisonous and thus will not tend to irritate the 50 nasal passages.

I further do not wish to be limited solely to the use of tobacco. As I have already described, 55 many other vegetable materials may be used, such as malt, licorice, eucalyptus and other herbs. They may be used either alone or in combination with tobacco. It is possible with my method to use the tobacco and other materials soon after 60

harvesting without the necessity for the usual long ageing process. Aromatic and medicinal characteristics may be given to my vapors. It should be further appreciated that in my process all parts of material may be used and there need be no separation of only the choice leaf portions as is necessary for the best conditions and ordinary smoking. I, therefore, do not wish to be limited by the specification and drawings, but only by the appended claims.

I claim:

1. A new product comprising tobacco smoke compressed to a relatively small fraction of its original volume to provide in highly concentrated form the desirable constituents only of tobacco smoke.

5

2. A combination comprising tobacco smoke compressed to a relatively small fraction of its original volume and a receptacle adapted to confine said compressed smoke.

10

JOSEPH Z. DALINDA.
